(57) **CLAIM**

The ornamental design for a combined information and advertising panel, as shown and described.

DESCRIPTION

FIG. 1 is a front perspective view of an example embodiment of an information/advertising panel assembly showing my new design.

FIG. 2 is a front view thereof.

FIG. 3 is a left side view thereof.

FIG. 4 is a top view thereof.

FIG. 5 is a right side view thereof; and,

FIG. 6 is a rear view thereof.

1 Claim, 6 Drawing Sheets
